ELECTROMAGNETS

Arvid E. Lillquist, Wauwatosa, Wis., assignor to Cutler-Hammer, Inc., Milwaukee, Wis., a corporation of Delaware

Application April 16, 1954, Serial No. 423,554

8 Claims. (Cl. 317—164)

This invention relates to improvements in electromagnets, and more particularly to improvements in the structural features of electromagnets used for lifting and the like.

In the construction of lifting magnets it has long been a problem to reduce their size and weight without reducing their lifting capacity or impairing their ability to withstand abuse. More recently the problem of reducing the current requirements has been brought into prominence by the adoption of new applications for lifting magnets. For example, where magnets are to be used on fork lift trucks with battery power, minimizing the amount of current drain is a vital feature.

Accordingly an object of the invention is to provide an improved electromagnet construction which for a given lifting capacity is smaller and lighter than electromagnets as heretofore proposed.

Another object of the invention is to effect a radical reduction in the current requirements of lifting magnets.

A further object of the invention is to provide an electromagnet having the aforementioned desirable characteristics while eliminating the necessity for the usual steel castings and the patterns required for producing the same.

Other objects and advantages of the invention will hereinafter appear.

Heretofore, because of the extremely rough usage encountered by lifting magnets it has been the practice to make the several parts thereof out of relatively heavy metal castings. My invention contemplates a reduction in the number of said parts and the fabrication of said parts out of readily available stock materials, such as metal plate, bar stock and tube stock. Although I will herein show and describe my invention in an embodiment which is especially adapted for use with fork lift trucks where the fork is used to pick up the magnet and the magnet is then used to pick up a magnetic metal plate or other magnetic material to be transported, it is to be understood that the invention is likewise applicable to magnets intended for other uses.

In the drawings, Figure 1 is a view in section on the line 1—1 of Fig. 2 illustrating the structural details of my improved electromagnet, and

Fig. 2 is a bottom plan view, on a reduced scale, of the electromagnet illustrated in Fig. 1.

In Figs. 1 and 2 of the drawings the numeral 10 designates the magnet frame, which is shown as machined from the required length of low cost readily obtainable (preferably round) bar stock of a suitable diameter, as indicated at the circular upper end portion 11 thereof. Said upper end portion is machined to provide a relatively large and relatively deep, preferably concentric, circular recess 12, which is utilized to provide a terminal box for wiring of the magnet.

As shown in Fig. 1, and in dotted lines in Fig. 2, an insulating block 13 is attached by screws 14, 14 to the bottom wall 12^a of recess 12. Although block 13 is shown as of the four terminal type, only two of the four terminal plates 15 are required to respectively electrically connect

2

the insulated terminal wires 16 and 17 of the magnet winding with the insulated terminal wires 18 and 19 from a suitable source of energy supply, such as a battery. A suitable opening 20 is drilled through the peripheral wall 5 of recess 12 to provide for insertion of the terminal wires 16 and 17 of the magnet winding.

A second opening 21 is drilled through the peripheral wall of recess 12; the inner end of said opening being of a size to provide clearance for the rubber covering 22 surrounding the aforementioned terminal wires 18 and 19. The outer end portion 21^a of opening 21 is of greater diameter; the same being tapped to accommodate a suitable packing gland 23 having an opening therethrough to accommodate with a rather close fit the aforementioned rubber covering 22. Prior to insertion of gland 23 a suitable amount of waterproof packing 21^b is forced into the space between the covering 22 and portion 21^a of opening 21, so that upon inward driving of gland 23 in a well known manner said packing is caused to tightly grip the rubber covering 22 and the inner end of portion 21^a of said opening, thus providing a watertight connection between said parts.

The magnet frame 10 has its lower end portion machined to provide a concentric circular cavity or recess 24. The aforementioned length of round bar stock from which frame 10 is fabricated is peripherally cut away as indicated at 25 to provide the downwardly facing horizontal annular shoulder 26. The periphery of said length of round bar stock is further cut away to slightly reduce the outer diameter of the lower end portion of frame 10, as indicated at 27 in Fig. 1. The vertical length of the cut away portion 25 preferably corresponds substantially exactly with the thickness of the top plate 28 of the magnet, whereas the balance of the downward length of frame 10 is adapted to freely accommodate the annular magnet coil or winding 29. Frame 10 is additionally peripherally cut away from a point adjacent its lower end as indicated at 30, and a peripheral groove 30^a is formed in cut away portion 30, preferably after frame 10, top plate 28 and outer pole member 33 have been united, for purposes hereinafter described.

The machining of frame 10 as aforescribed provides an annular inner pole face 31 of preselected dimensions with respect to the dimensions of the outer pole face 32 of the outer pole member 33, which will now be described. Said outer pole member 33 is initially cut to the required length from standard commercial pipe of the desired inner and outer diameters. The inner periphery of the upper end of said length of pipe is annularly machined or otherwise cut away to provide a pair of right-angled shoulder portions 34, and the top plate 28 of the magnet is provided with a downwardly facing circular groove 35 of rectangular form in cross section the inner periphery of which is adapted to have a rather close fit with the corresponding vertical shoulder 34 formed on said pole member 33. Alternatively said outer pole member 33 could readily be fabricated by rolling a cylinder from a bar or plate of proper thickness and joining the ends thereof by welding.

The lower end of outer pole member 33 is preferably machined to provide the upwardly and inwardly extending beveled surface 36, and the inner diameter of member 33 is likewise increased by machining adjacent the beveled surface 36, as indicated at 37. The upper end of the cut away portion 37 is aligned with the upper end of the cut away portion 30 of the inner pole 31 of the magnet. Also formed in the surface of cut away portion 37 of outer pole member 33 is a groove 37^a, which is aligned with the aforementioned groove 30^a in the frame member 10 when the magnet frame 10, top plate 28 and outer pole member 33 are assembled with respect to each other.

Top plate 28 and magnet frame 10 are preferably as-

sembled and rigidly and permanently united in the relative positions thereof illustrated in Figs. 1 and 2. For example, the top plate 28 may be seated upon a support of suitable form (not shown), and the lower end of magnet frame 10 then inserted downwardly with a rather close fit through the circular opening 28^a provided in top plate 28, until the annular shoulder 26 on said frame seats against the upper surface of said top plate. Said parts may then be permanently united by a sealed connection represented by the continuous single weld 38 around the adjacent surfaces of top plate 28 and the upper end portion 11 of magnet frame 10.

After so uniting top plate 28 and magnet frame 10 such assembly is preferably turned upside down, whereupon the outer pole member 33 is moved downwardly with respect to top plate 28 until the shouldered end portion 34 thereof is seated within the circular groove 35 in top plate 28, with the aforementioned close fit thereof with the inner vertical shoulder 34 of said groove. While said outer pole member 33 is rigidly held in engagement with top plate 28 said parts are rigidly and permanently united by a sealed connection represented by the continuous weld 40 around the adjacent portions of outer pole member 33 and top plate 28.

With frame 10, top plate 28 and outer pole member 33 so united, and positioned as last mentioned, the magnet coil 29 may be inserted into the annular recess afforded by said parts; care being taken to insure that the terminal wires 16 and 17 of the magnet coil 29 are alined with and inserted through the opening 20 into terminal recess 12. Prior to insertion of magnet coil 29 I prefer to first slide over the magnet frame 10 a slotted washer 39 (Fig. 1) of suitable insulating material. The slot 39^a (Fig. 1) in said washer is alined with said opening 20 leading to terminal recess 12; said slot accommodating the insulated terminal wires 16 and 17 of coil 29, as shown.

While the aforementioned assembled parts are allowed to remain in inverted position, the space around coil 29 is filled with a suitable impregnating compound 41 in molten or liquid condition, up to or substantially in line with the horizontal annular shoulder 37 (Fig. 1). Thereafter the annular non-magnetic metal coil shield 42 is placed in position, as shown, in contact with the fill of impregnating material 41. If necessary or required to effect proper tight clamping of coil 29 in position by the annular metal plate 42 forming the coil shield when the latter is properly positioned and secured, and annular insulating spacing washer (not shown) may be interposed between coil shield 42 and the fill of impregnating compound 41.

With coil shield 42 pressed into the desired position, as shown, in any suitable or desired manner, the same is caulked, as indicated at 43 and 43^a in Fig. 1, by use of the required lengths of string babbitt of suitable gauge (such as No. 7 Brown & Sharpe).

Prior to closure and sealing of the open upper end of wiring terminal recess 12 (Fig. 1) the terminal wires 16 and 17 of the magnet coil 29 are respectively attached by suitable binding screws or the like to two of the wiring terminal plates 15 (Fig. 2) and the lead wires 18 and 19 are likewise attached to said terminal plates respectively; the rubber covered lead-in conductor 22 containing wires 18 and 19 being provided with a water-tight seal or connection in hole 21, 21^a by the aforementioned packing material 21^b and the screw-threaded stuffing gland 23. Thereupon the gasket 44 of rubber or similar waterproof material and metal cover plate 45 are positioned as shown over the open upper end of recess 12 and secured thereto by a suitable number of clamping bolts, two of which are shown at 46; the threaded shanks of bolts 46 penetrating alined openings in plate 45 and gasket 44 and taking into tapped recesses (not shown) in the upper end portion 11 of magnet frame 10.

In the manner aforescribed all parts of the magnet coil 29 and the wiring elements therefor are effectively

sealed against the entrance of moisture or liquids of any kind. As aforesated the conductor 22 is of sufficient length to connect with a suitable source of energy, such as a battery upon a forked lift truck or the like.

5 When used as a lift truck mounted magnet the top plate 28 is provided with two pairs of arms or extensions 28^a, 28^b, and 28^c, 28^d; said top plate 28 having rigidly attached to the lower face thereof two pairs of downwardly projecting rectangular metal studs 28^e, 28^f, and 28^g, 28^h; each of said studs being shown as fillet welded, along at least two sides thereof, to its associated arm or extension of plate 28 (see Fig. 2).

When a magnet like that herein illustrated is used with a fork lift type truck, the same is inserted between the 15 two spaced projections of the truck fork, so that the bottom surfaces of the pairs of projections 28^a, 28^b and 28^c, 28^d overlie the respective prongs of the fork; the respective pairs of studs 28^e, 28^f and 28^g, 28^h being positioned between the inner edges of the fork prongs. The fork lift 20 truck may be provided with any suitable known means to prevent endwise sliding movement of the magnet relatively to the fork.

Assuming that the outer pole of a magnet like that herein disclosed has an outside diameter of twelve inches the 25 weight of the complete device illustrated would be ninety pounds, and the rated lifting capacity of the magnet (for lifting dock plates, for example) would be as follows, for half time duty:

	Thickness of dock plate	Maximum Lift, pounds	Maximum Size, feet
30			
35	One-quarter inch.....	290	5 by 5
	Five-sixteenths inch.....	500	6 by 6
	Three-eighths inch.....	680	6 by 7
	Seven-sixteenths inch (or more).....	900	7 by 7

In practice I prefer to fabricate the magnet frame 10 from the required length of hot rolled low carbon steel of 40 round cross-section as aforementioned. The outer pole 33 of the magnet is preferably machined from a section of the required length of cold drawn seamless low carbon steel tubing. The top plate 28 is preferably formed in any suitable manner from a plate of hot rolled low carbon steel; and the metal cover plate 45 for the wiring terminal recess 12 is preferably punched from a sheet of hot 45 rolled low carbon steel.

It will be apparent to those skilled in the art that the 50 basic design herein disclosed may be utilized in making other sizes of relatively small magnets. It is also to be understood that a magnet of the character herein contemplated may be built without the supporting arms of the top plate, or in such form that the magnet can be carried by lugs and chains, along the lines of conventional forms 55 of lifting magnets.

As aforesaid the magnet specifically shown and 60 described herein was designed to lift plates of various sizes from one-fourth inch to seven-sixteenths inch thick; it being understood that the greatest magnetic pull would be on the seven-sixteenths inch plate; it also being understood that the greatest amount of magnetic flux would be carried through the magnet into a plate of the last mentioned thickness. If the plate to be handled is greater than seven-sixteenths inch thick the proportional sizes or 65 areas of the inner and outer poles of the magnet may readily be modified or varied, using the same basic stock materials, in order to obtain more magnetic pull.

Also it will be apparent to those skilled in the art that 70 a magnet such as that herein disclosed may be modified or designed, using the same basic stock materials, to handle scrap or heavy plate. The only differences in such a modified magnet from that herein disclosed would be that the inner pole face of the magnet would be left solid (by not machining the magnet frame to provide 75 the recess 24); the chamfer 36 at the inside diameter of

the outer pole face 32 would be omitted; and the thickness of the top plate (to be substituted for top plate 28) would be approximately twice as great, with a corresponding increase in the total height of the magnet frame.

Various other modifications in the details of construction of the magnet herein disclosed may be made without departing from the spirit and scope of my invention as defined in the appended claims.

I claim:

1. In an electromagnet of relatively small size with reference to its lifting capacity, in combination, a magnet frame consisting of a preselected length of magnetic steel bar stock of suitable cross-section to provide an inner pole, said frame having a downwardly facing peripheral shoulder formed thereon intermediate the upper and lower ends thereof and a second downwardly facing shoulder of smaller cross-sectional dimensions formed thereon adjacent the lower end thereof, a wiring terminal recess formed in the upper end of said magnet frame, a flat top plate of magnetic steel, said top plate having an opening formed therein to permit insertion and positioning of said frame with said first mentioned shoulder seated against said plate, a continuous peripheral welded and sealed connection between said top plate and said frame to permanently unite the same, an outer pole member of tubular form composed of magnetic steel, one end of said outer pole member being united with said top plate by a continuous peripheral weld, a magnet coil positioned between said frame and said outer pole member and having its terminal wires located within said terminal recess, and a coil shield of non-magnetic metal underlying said magnet coil between said outer pole member and said inner pole and having a sealed connection with each pole.

2. An electromagnet of the character defined in claim 1, wherein means are provided to afford exit of a plurality of conducting wires from said terminal recess through a sealed opening, a metal member overlying the open end of said terminal recess and removably secured thereto, and a gasket interposed between said metal member and said recess to effect sealing of the latter.

3. In an electromagnet of relatively small size with reference to its lifting capacity, in combination, a magnet frame consisting of a preselected length of low carbon steel bar stock of round cross-section to provide an inner pole, said frame having a reduced lower end a wiring terminal recess formed in the upper end thereof, said frame also having a peripheral annular shoulder formed thereon at a predetermined point in the length thereof, a flat top plate of low carbon steel, said top plate having an opening formed therein to permit insertion of the reduced end of said frame to effect seating of said peripheral annular shoulder against one face of said plate, a continuous peripheral welded and sealed connection between said top plate and said frame to permanently unite the same, said top plate having a circular groove formed in the other face thereof, an outer pole member of cylindrical form composed of low carbon steel, one end of said outer pole member being adapted to seat within said groove, a continuous peripheral welded and sealed connection between said top plate and said outer pole member, a magnet coil positioned between said frame and said outer pole member and having its terminal wires located within said terminal recess, a coil shield of non-magnetic material underlying said magnet coil between said outer pole member and said inner pole and having a sealed connection with each pole, and said top plate having two like pairs of arms formed integrally therewith and respectively extending from opposite sides thereof substantially beyond the periphery of said outer pole member, for the purpose set forth.

4. As an article of manufacture, a frame for an electromagnetic lifting magnet of relatively small size with respect to its lifting capacity, said frame consisting of a single piece, of desired length, of magnetic steel round

bar stock, said piece having at least three portions of its length of different outside diameters, the upper end portion being of greatest diameter and providing a downwardly facing annular shoulder adapted to seat against

5 the upper surface of a perforated sheet metal top plate for the magnet, the lower end portion being of smallest diameter and providing a downwardly facing annular shoulder, an annular non-magnetic metal coil shield the inner portion of which is adapted to seat against said shoulder, the upper end of said frame having therein an upwardly opening wiring terminal recess of substantially cylindrical contour, and means comprising a metal plate and an interposed sealing gasket secured to the upper end of said frame and overlying the open end of said recess

15 to assist in rendering the same liquid tight.

5. As an article of manufacture, a frame for an electromagnetic lifting magnet of relatively small size with respect to its lifting capacity, said frame consisting of a single piece, of desired length, of magnetic steel round

20 bar stock, said piece having at least three portions of its length of different outside diameters, the upper end portion being of greatest diameter and providing a downwardly facing annular shoulder adapted to seat against the upper surface of a perforated sheet metal top plate for

25 the magnet, the lower end portion being of smallest diameter and providing a downwardly facing annular shoulder, an annular non-magnetic coil shield the inner portion of which is adapted to seat against said shoulder, the upper end of said frame having therein an upwardly

30 opening wiring terminal recess of substantially cylindrical contour, means comprising a metal plate and an interposed sealing gasket secured to the upper end of said frame and overlying the open end of said recess to assist in rendering the same liquid tight, and the lower end of

35 said frame having therein a downwardly opening recess of substantially cylindrical contour to provide an annular inner pole face whose total active area bears a predetermined proportionality to the thickness of said top plate.

6. As an article of manufacture, a frame for an elec-

40 tromagnetic lifting magnet of relatively small size with respect to its lifting capacity, said frame consisting of a single piece, of desired length, of low carbon steel round bar stock, said piece having at least three portions of its length of different outside diameters, the upper end

45 portion being of greatest diameter and providing a downwardly facing annular shoulder adapted to seat against the upper surface of a perforated sheet metal top plate for the magnet, the lower end portion being of smallest diameter and providing a downwardly facing annular

50 shoulder, an annular non-magnetic metal coil shield the inner portion of which is adapted to seat against said shoulder, the upper end of said frame having therein an upwardly opening wiring terminal recess of substantially cylindrical contour, means comprising a metal plate

55 and an interposed gasket secured to the upper end of said frame and overlying the open end of said recess to assist in rendering the same liquid tight, and the lower end of said frame having therein a downwardly opening recess of substantially cylindrical contour to provide an annular inner pole face whose total active area bears a predetermined proportionality to the thickness of said top plate.

7. In an electromagnet of relatively small size with reference to its lifting capacity, in combination, a mag-

65 net frame consisting of a preselected length of magnetic steel bar stock of round cross-section to provide an inner pole, said frame having a wiring terminal recess formed in the upper end thereof, said frame also having a peripheral shoulder formed thereon at a predetermined point in the length thereof, a top plate of magnetic

70 steel, said top plate having an opening therein to permit insertion of one end of said frame to effect seating of said peripheral shoulder against one face of said plate, a continuous peripheral welded and sealed connection

75 between said top plate and said frame to permanently

unite the same, said top plate having a circular groove formed therein, an outer pole member of tubular form composed of magnetic steel, one end of said outer pole member being adapted to seat within said groove, a continuous peripheral welded and sealed connection between said top plate and said outer pole member, a magnet coil positioned between said frame and said outer pole member and having its terminal wires located within said terminal recess, and a non-magnetic coil shield underlying said magnet coil between said outer pole member and said inner pole and having a sealed connection with each pole.

8. In an electromagnet of relatively small size with reference to its lifting capacity, in combination, a magnet frame consisting of a preselected length of magnetic steel bar stock of round cross-section to provide an inner pole, said frame having a wiring terminal recess formed in the upper end thereof, said frame also having a peripheral shoulder formed thereon at a predetermined point in the length thereof, a top plate of magnetic steel, said top plate having an opening therein to permit insertion of one end of said frame to effect seating of said peripheral shoulder against one face of said plate, a continuous peripheral welded and sealed connection between said top plate and said frame to permanently unite the same, said top plate having a circular groove formed therein, an outer pole member of tubular form com-

5 posed of magnetic steel, one end of said outer pole member being adapted to seat within said groove, a continuous peripheral welded and sealed connection between said top plate and said outer pole member, a magnet coil positioned between said frame and said outer pole member and having its terminal wires located within said terminal recess, a non-magnetic coil shield underlying said magnet coil between said outer pole member and said inner pole and having a sealed connection with each pole, means affording exit of a plurality of conducting wires from said terminal recess through a sealed opening, a metal member overlying the open end of said recess and removably secured thereto, and a gasket interposed between said metal member and said recess to seal the latter.
